UNITED STATES PATENT OFFICE

BALDOMERO VIRGILIO SOUTO, OF NEW YORK, N. Y., AND WILLIAM PHILLIPS COM-
STOCK, OF NEWARK, NEW JERSEY

PARLOR-CAR CHAIR

Application filed March 23, 1929. Serial No. 249,400.

This invention relates to parlor car chairs that are transformable into berths.

The invention comprises combinations of demountable backs, folding arms, and traveling pedestals that make it possible to get a variety of combinations that may be used in a parlor car or in a combined parlor and sleeping car.

The invention comprises as a principal feature upholstered seat and side arms, the latter being provided with hinges that will be lowered below the top of the seat when the arms are hinged down into horizontal positions.

Another feature of the invention comprises a combination of a demountable rectangular back for the chair to be used in an upright position for arm chair use and in a horizontal position with the arms turned down to form a bench.

Another feature comprises means for moving the chair on a track, the chair being carried on a truck for this purpose and provided with means for shifting the weight of the chair from the truck to the floor and vice versa.

Other minor features will be described in connection with the accompanying drawings, in which

Figure 1 is a front elevation of the chair.

Figure 2 is a side elevation.

Figure 3 is an enlarged view of the arm holding mechanism.

Figure 4 is a detail section of the same on line 4—4 of Figure 3.

Figure 5 is a horizontal section on line 5—5 of Figure 3.

Figure 6 is a front elevation partly in section of the arm holding mechanism in its raised position.

Figure 7 is a similar view in the lowered position.

Figure 8 is a horizontal sectional view of the lock and key for the arm mechanism.

Figure 9 is a side view of the lower end of the back.

Figure 10 is a back view of the same.

Figure 11 is a side view showing the bolt connecting the arm with the back.

Figure 11^a is a back view of the same.

Figure 12 is a plan view of the same.

Figure 13 is a detail view of the same.

Figure 14 is a front view of the chair made into a bench.

Figure 15 is a side view of the same.

Figure 16 is a section through part of the chair back and the wall on line 16—16 of Figure 14.

Figure 17 is a longitudinal section through the chair pedestal showing the truck and the conduit therefor.

Figure 18 is a horizontal section on line 18—18 of Figure 17.

Figure 19 is a transverse vertical section on line 19—19 of Figure 17 showing the chair pedestal resting on the floor.

Figure 20 is a similar view showing the pedestal carried by the truck.

The chair is made up of four principal members comprising a pedestal 1, seat 2, arms 3, and back 4. The seat, arms and back are made in rectangular box form and are upholstered in the usual manner to form cushioned surfaces. One of the objects of the invention is to make a berth out of the seat and arms, and for this purpose, the arms are hinged to the seat or to the chair frame carrying the seat so that the arms may be turned down and form extensions of the seat to make a horizontal berth. It is desirable that the hinges shall not approach near enough to the upholstered surface of the berth to be felt by a figure recumbent thereon, and the hinges now to be described have the function of dropping below the surface of the seat when the arms are lowered. The hinges comprise two members 5 and 6 united by pivots or pintles 7. The members 5 are securely fastened to the lower edges of the arms 3 while the members 6 are made slideable within guides 8 secured to the seat or more properly to the chair frame supporting the seat, the chair frame being indicated at 9. Pivoted at 10 to the guide 8, and therefore to the chair or seat, are elements 11 of toggles which in turn are pivoted at 12 to toggle elements 13, the upper ends of which are pivoted at 14 to the outside of the arms 3. The length of elements 11 and 13 is such that when in their extended position, as shown in Figure 6, the

arms 3 will be held in their uppermost position with pivots 7 about on the level with the top of the seat 2 and the arms slightly overhanging the seat, as is usual in arm chair construction. When, however, the toggle is collapsed, as shown in Figure 7, the members 6 slide downward through the guides 8 as the arm is swung outward until the members 5 rest on top of the guides 8, at which time the toggle members in their collapsed condition form diagonal braces for the support of the arms, as shown in Figure 7. When in the elevated position, the toggles are held rigid by means of bolts 15 which are slidable against the outside surface of the members 13 so as to hold said members rigidly vertical and close against the sides of the arms. The bolts are guided in a guide housing 16 and are held resiliently in their locking position by means of springs 17 having for abutments lugs 18 on the side of the arms. The bolts may be retracted by means of connecting rods 19 and cranks 20, the cranks having shafts pivoted in the side of the chair as at 22, and provided with square heads 23 over which may be fitted an operating key 24. When the key is placed on the shaft, a slight twisting motion will withdraw the bolts 15 so as to release the members 13, whereupon the arm may be lowered into the position shown in Figure 7, so that the upholstered surface of the arm will lie flush and closely adjacent to the upholstered surface of the seat, and yet the hinge pivot 7 will have been lowered to a position sufficiently below the upholstered surfaces as to not be capable of being felt by a person lying on the berth. As the bolts 15 are released when the arms are lowered, they slide over the members 13 and have edges that make a flat contact with said members while in motion and release at the end of the motion to lock the arms in their lowered position by sliding into the angular space between the toggle members. In order to prevent the possibility of the lowered arms being tipped up, the members 11 may have dogs 11' adapted to engage in openings 6' in the slidable member 6 when the arms are lowered, which dogs will act as locks to prevent the rocking of the arm members by any pressure applied on the outer edge of the arms. The chair seat is mounted on the pedestal 1 with a swivel so that it may be swung to different horizontal angles. This makes it permissible to swing the chairs at any desired angle when used as chairs, and when used as a berth, to move the chairs with their longest dimensions parallel, three such chairs when moved into juxtaposition forming a berth of the conventional size. The chairs may also be converted into benches. For this purpose, the backs 4 are made of greater height than width and are demountable from the chairs. They are supported by hinged stirrups or brackets 25 which depend from the bottom

of the chair frame at the back. These stirrups 25 are, as shown in Figures 9 and 10, made of round rod bent to conform to the shape of the lower edge of the back, having a lip 26 at the outer end to hold the back against the chair. The arms 3 are provided with slideable bolts 27 (see Figure 11) which have lugs 28 on their outer ends adapted to be turned in behind the backs to hold the backs firmly to the arms, the bolts having heads 29 to limit their outward extension. When the backs are demounted, the bolt is turned so that the lugs 28 will pass by the side of the backs and may be pushed into pockets 30 in the ends of the arm, the bolt itself sliding into the pocket 31. When the backs are demounted from the chair assembly, they may be turned on their side, and assembled as a bench back for the bench, made up of the seat 2 and the arms 3 in their lowered position, as shown in Figure 14. When made up as a bench in this manner, supplemental arms 32 may be provided on the outer edges of the arms 3. The supplemental arms are provided with latches or hook members 33 which when the arms are not in use, may be folded into pockets 34, and when the arms are assembled on the bench, engaged under the bench so as to lock the said supplemental arms in place. When used as a bench, it is purposed to have the bench pushed up against a wall shown at 35, and as a means of securing the backs and supplemental arms to the wall, we have shown pivoted latches 36 (see Figure 16) which, when not in use, may be folded into pockets 37 in the wall, and yet may be pulled out and form supporting hooks engaging with latch-plate 38 on the back and arms. In order to move the chair about in the car for the purpose of assembling two or more of the chairs into a berth or for the purpose of moving the chair frame up to a wall to form a bench as before described, we employ a truck operating in an underfloor conduit 39, the upper flanges 40 of which are separated so as to form a slot 41. The truck comprises a frame 42 having vertical extensions 43 that pass down through the slot 41 and carry journals 44 for truck wheels 45. The pedestal 1 is made hollow as shown so as to cover the frame 42, and the frame has vertical extensions 46 that pass up through a transverse bar 47 of the pedestal and are united at the top by a cross arm 48. An eccentric or cam 49 occupies the space between the member 47 and the member 48. The cam has a shaft 50 which extends through the side of the pedestal and has a lever 51 which may be operated by the foot or otherwise. Springs 52 tend to occupy the space between the frame 42 and the member 47 and form a resilient support for the chair when it is being moved. To move the chair, the lever must be in the position shown in Figure 20, that is, up. When, however, the lever is de-

pressed as in Figure 19, the cam acting on member 48 lifts the frame 42 until the truck wheels are clear of the floor of the conduit, at the same time lowering the pedestal to rest firmly on the floor. Flanges 53 on the frame engage under the flanges 40 on each side of the slot 41 when the lever 51 is depressed, and lock the chair securely to the floor. At 54 is shown a trap door at the end of the conduit through which the truck may be removed in case it is desired to remove the chair from the car.

The above specification gives a description of a preferred embodiment of the invention, but many of the details should be regarded as only specific means of carrying out the general idea, and may be varied considerably without departing from the spirit of the invention.

20. We claim:

1. A parlor car chair comprising in combination, upholstered side arms and seat, vertically movable hinges jointing the arms to the seat to permit the arms to be turned down from a vertical to a horizontal position closely adjacent the seat, means for holding the pivotal members of the hinge in an upper position when the arms are vertical, means for supporting the said pivotal members in a lower position when the arms are lowered, and means for locking said holding means when the arms are upright, said holding means comprising toggles and said locking means comprising bolts for holding the toggles in their extended position.

2. A parlor car chair comprising in combination, upholstered side arms and seat, vertically movable hinges jointing the arms to the seat to permit the arms to be turned down from a vertical to a horizontal position closely adjacent the seat, means for holding the pivotal members of the hinge in an upper position when the arms are vertical, means for supporting the said pivotal members in a lower position when the arms are lowered, and means for locking said holding means when the arms are upright, said holding means comprising toggles and said locking means comprising bolts for holding the toggles in their collapsed position forming brackets supporting the lowered arms.

3. A parlor car chair comprising in combination, a chair frame, an upholstered seat and upholstered arms, hinges having two members united by a pivot, one member of each hinge secured to an arm and the other member slidable vertically on the chair frame, guides on the frame for said slidable members, means for holding the said hinge members in their elevated positions and means for releasing said holding means to allow the arms to be swung out on the hinges and the hinges lowered to be below the surface of the

the seat when the arms are in their lowered position.

4. A parlor car chair comprising in combination, a chair frame, an upholstered seat and upholstered arms, hinges having two members united by a pivot, one member of each hinge secured to an arm and the other member slidable vertically on the chair frame, guides on the frame for said slidable members, means for holding the said hinge members in their elevated positions and means for releasing said holding means to allow the arms to be swung out on the hinges and the hinges lowered to be below the surface of the seat when the arms are in their lowered position, said holding means comprising toggle members that in their extended relation form outside braces for the arms and in their folded relation form a bracket upon which the arms rest.

5. A parlor car chair comprising in combination, a chair frame, an upholstered seat and upholstered arms, hinges having two members united by a pivot, one member of each hinge secured to an arm and the other member slidable vertically on the chair frame, guides on the frame for said slidable members, means for holding the said hinge members in their elevated positions and means for releasing said holding means to allow the arms to be swung out on the hinges and the hinges lowered to be below the surface of the seat when the arms are in their lowered position, said holding means comprising toggles hinged at one end to the chair frame and at their other ends to the arms.

6. A parlor car seat comprising in combination, an upholstered seat and upholstered side arms, vertically slidable hinge members connecting the arms with the seats, and toggle levers connecting the seat with the arms to slide the hinges downward as the arms are swung outward on the hinges.

7. A parlor car chair comprising in combination, a chair frame, a seat, side arms, hinges connecting the side arms to the chair and adapted to support the side arms vertically to form an arm chair or horizontally to form an extension seat for a bench and a demountable rectangular back adapted to be secured to the chair and to the side arms in their upright position to form an arm chair or to be supported with its longer sides horizontal at the back of the chair and the lowered side arms to form a bench, with a supporting bracket on the chair for the lower edge of the back and means for securing the back to the arms, comprising an L-shaped bolt slidably mounted in the arms.

8. A parlor car chair comprising in combination, a chair frame, a seat, side arms, hinges connecting the side arms to the chair and adapted to support the side arms vertically to form an arm chair or horizontally to form an extension seat for a bench and a demount-

able rectangular back adapted to be secured to the chair and to the side arms in their upright position to form an arm chair or to be supported with its longer sides horizontal at the back of the chair and the lowered side arms to form a bench, and demountable side arms with means for securing the same to the lowered hinged side arms.

9. A parlor car chair comprising in combination, a chair frame, a pedestal for said frame, a wheeled truck supporting the pedestal, a slotted car floor, means for shifting the weight of the pedestal and chair from the truck to the floor, and means extending through the slot for clamping the pedestal to the floor.

10. A parlor car chair comprising in combination, a chair frame, a hollow pedestal supporting said frame, a truck-way beneath the floor having side flanges at the top with a slot between them, a wheeled truck in said truck-way, a support for the pedestal on the truck passing through the said slot, means within the pedestal for lifting the support to elevate the truck and let the pedestal rest on the floor, and means on the support engaging the under side of the floor when the truck is so lifted to clamp the pedestal to the floor.

11. A parlor car chair comprising in combination, a chair frame, a hollow pedestal supporting said frame, a truck-way beneath the floor having side flanges at the top with a slot between them, a wheeled truck in said truck-way, a support for the pedestal on the truck passing through the said slot, means within the pedestal for lifting the support to elevate the truck and let the pedestal rest on the floor, an operator's lever outside the pedestal connecting with the lifting means inside the pedestal.

12. A parlor car chair comprising in combination, a chair frame, a hollow pedestal supporting said frame, a truck-way beneath the floor having side flanges at the top with a slot between them, a wheeled truck in said truck-way, a support for the pedestal on the truck passing through the said slot, means within the pedestal for lifting the support to elevate the truck and let the pedestal rest on the floor, an operator's lever outside the pedestal connecting with the lifting means inside the pedestal, the said lifting means being self-locking in each of its extreme positions.

13. A parlor car chair comprising in combination, a chair frame, a pedestal for said frame, a wheeled truck supporting the pedestal, a slotted car floor, means for shifting the weight of the pedestal and chair from the truck to the floor, and means extending through the slot for clamping the pedestal to the floor, the said supporting means having a resilient member between the truck and the pedestal for spring supporting the chair when free of the floor.

14. A parlor car chair comprising in combination, a chair frame, an upholstered seat and upholstered arms, hinges having two members united by a pivot, one member of each hinge secured to an arm and the other member slidable vertically on the chair frame, guides on the frame for said slideable members, means for holding the said hinge members in their elevated positions, means for releasing said holding means to allow the arms to be swung out on the hinges and the hinges lowered to be below the surface of the seat when the arms are in their lowered position, and means for locking the vertically slideable member in its lowered position.

15. A parlor car chair comprising in combination, upholstered side arms and seat, vertically movable hinges jointing the arms to the seat to permit the arms to be turned down from a vertical to a horizontal position closely adjacent the seat, means for holding the pivotal members of the hinge in an upper position when the arms are vertical, means for supporting the said pivotal members in a lower position when the arms are lowered, and means for locking said holding means when the arms are lowered, said holding means comprising toggles and said locking means comprising bolts for holding the toggles in their extended position.
